UNITED STATES PATENT OFFICE

ELMER ZEBLEY TAYLOR AND SAMUEL PARKIN LEDGARD, OF NEWARK, NEW JERSEY

CLOSURE FOR PAPER OR OTHER CONTAINERS

Application filed June 30, 1926, Serial No. 119,711, and in Great Britain April 21, 1926.

The object of this invention is to provide a lid or closure for containers, tins, boxes and the like, particularly those which are made of paper or like material, and which lid or closure shall form an efficient seal to the container until it is desired to open the latter, and shall subsequently be capable of being opened and closed as required.

The invention is illustrated in the accompanying drawings, in which

Fig. 1 is a plan view of the improved lid or closure;

Fig. 2 a sectional view of part of a container with the lid or closure inserted;

Fig. 3 a similar view but showing the closure opened to permit access to the contents, and

Fig. 4 a view similar to Fig. 2 but showing a slight modification.

In carrying out the invention a disc A of woodpulp board or other suitable material is employed, such disc being of the required size to fit into the groove or recess B provided for it in the upper end of container C. In the under surface of disc A a circular line D is scored partially through the material, and in the upper surface another circular line E of larger diameter is also scored; the line E may be continuous but preferably not a complete circle but being interrupted as shown at F for the purpose hereinafter described. The scoring of either or both the lines D and E may be in the form of complete lines as shown, or may consist of a series of short dashes with intervening unscored spaces.

The object of the scored lines D and E is that when it is desired to open the container C to which the closure has been applied, this can be readily effected by inserting a fork, knife or other instrument into the scored line E and prizing up the material, when the scoring will cause such material to break between the lines D and E so that the central portion of the closure can be raised, as shown in Fig. 3, the part F where the scored line E is interrupted acting as a hinge for the portion raised.

If desired a tab shaped outward extension of the line E may be formed, as shown in

dotted lines at G, at a point preferably opposite the point F, and which will act both as a guide for the insertion of the opening instrument and, when the opening has been started, as a tab to be grasped by the fingers 55 to complete it, and for subsequent use when the container is to be opened or closed.

It will be seen that the result of the breaking of the material between the scored lines is that the central or opening part of the closure will have a stepped edge, as shown clearly in Fig. 3, which in combination with the correspondingly stepped outer or stationary part of the closure will form a good joint when the opening part is subsequently closed, 60 and prevent such opening part from being pushed down into the container.

In the modification shown in Fig. 4 the scored lines D and E are of relatively larger diameter than in the arrangement shown in 70 Figs. 1, 2 and 3, so that when the lid is opened in the same manner as above described the edge of the opening part, formed by the scored line E, shall be quite close to the turned over edge H of the top of the container, so that it has to be sprung past such edge H to open or close, such edge H thus forming a means of overcoming the spring of the material and keeping the lid closed after it has once been opened. If a tab as G, Fig. 1, is 75 formed in line E, such tab may be of such length as to catch under the edge H for the same purpose.

It will be seen that the closure above described presents the advantage that it can 85 be easily applied to the container, and secured in the groove B therein by turning over the edge H of the container, and that when thus secured it forms an efficient closure, but one which can be readily opened when it is desired to gain access to the contents, and can 90 be closed again subsequently to protect such contents from exposure.

Although the lines D and E have been described above as being of circular form, it 95 will be readily understood that they may be of square, oval, rectangular or other configuration, and further that the complete closure may be made of any desired shape to suit 100

that of the container to which it is to be applied.

What we claim and desire to secure by Letters Patent is:—

- 5 1. In combination, a container, a closure applied thereto, the wall of said container being inturned at the upper edge and securing the closure in place, said closure having a scored line on the under side thereof to permit the central part to be raised when desired to open the container, and also having a scored line on the upper side formed and positioned so near the edge of the inturned portion of the wall that the said turned over
- 10 15 upper edge of the container will operate to prevent the inner or central part of the closure from springing open.
- 20 2. In combination, a container, a closure applied thereto and adapted to be secured therein by turning over the upper edge of the wall of the container into contact therewith, said closure having a scored line on its under face and a scored line on its upper face disposed outside the scored line on the under
- 25 30 face, said scored lines being so positioned that the material between them can be broken when it is desired to open the container, and the upper scored line being so formed and positioned that the edge of the opening part of the closure formed thereby has to be sprung past the turned-over upper edge of the container when it is desired to open or close the latter, as set forth.

In witness whereof we have signed this specification.

ELMER ZEBLEY TAYLOR.

SAMUEL PARKIN LEDGARD.
